(57) **CLAIM**

The ornamental design for the “revetment block,” as shown and described.

DESCRIPTION

FIG. 1 is a top perspective view of the “revetment block” showing our new design;

FIG. 2 is a top plan view thereof;

FIG. 3 is a bottom plan view thereof;

FIG. 4 is a right-side elevation view thereof, the left-side view being a mirror image of that shown; and,

FIG. 5 is a front elevation view thereof, the rear view being a mirror image of that shown.

1 Claim, 5 Drawing Sheets

FIG 1.

FIG. 2

FIG. 3

FIG. 4

FIG. 5
